HIS ATTORNEY

UNITED STATES PATENT OFFICE.

DANIEL J. MURNANE, OF SAN MATEO, CALIFORNIA, ASSIGNOR TO NON-PRESSURE GLAZING COMPANY, OF SAN FRANCISCO, CALIFORNIA, A CORPORATION OF CALIFORNIA.

SASH FOR HOLDING GLASS.

Application filed May 22, 1926. Serial No. 110,874.

My invention relates to window sashes and particularly to metallic window sashes used for holding large and heavy sheets of plate glass.

5 One of the objects of my invention is to provide a sash of few parts and simple construction which will exert no clamping action upon the glass.

Another object of my invention is to provide 10 a sash embodying improved means for securing the parts together.

A further object of my invention is to provide means for preventing the distortion of the fixed member of the sash prior to the complete 15 assembly of the sash.

My invention possesses other objects and features of advantage some of which with the foregoing will be set forth in the following description of the preferred form of my invention which is illustrated in the drawings accompanying and forming part of this specification. It is to be understood that I do not limit myself to the showing made by said drawings and description, as I may adopt variations of the preferred form within the scope of my invention as set forth in the claims.

In the drawings: Figure 1 is a vertical 30 sectional view thru a sash constructed according to my invention, and showing a plate of glass held therein. Figure 2 is a plan view of a portion of the adjustable sash bar and the tie bar. Figure 3 is a detail partly in vertical section, showing the bridge and screw construction of the sash. Figure 4 is a sectional view of the deformable end of the tie bar, the plane of section being indicated by the line 4—4 of Figure 2. Figure 5 is a detail showing the end of the clamping screw.

40 In terms of broad inclusion the sash of my invention comprises a stationary or fixed member adapted to engage one side of the glass, and an adjustable member adapted to engage the other side of the glass. Each of these members is formed in one piece, preferably of metal, and the stationary member is formed with a top glass-engaging flange and with a base flange. The base flange is provided with a raised seat to which is secured, at spaced intervals, a plurality of bridge members. Means are provided for securing the adjustable member to the stationary member, and comprise a plurality of similarly shaped tie bars each interlocked with the ad-

justable member, and provided with an extension overlying the seat beneath the bridges. A plurality of screws threaded one in each of the bridges and each provided with a head on the lower end thereof, constitute the means for securing the tie bars to the fixed member. The screws are constructed of sufficient length so that before the sash is assembled, and the fixed member alone is secured in position on the supporting structure, the screws may be backed out to engage the top flange of the fixed member so as to form a support therefor, thereby preventing the top flange of the fixed member from becoming distorted by workmen stepping thereon, or by objects falling on the top flange.

More specifically my improved sash comprises a stationary member having a wall 2 adapted to be secured to the wooden frame 3. Along its upper edge the wall 2 is extended in a top flange 4 for engagement with the plate glass 5. At its lower edge the wall 2 is extended in a base flange comprising the raised seat flange 6 and the foot flange 7, the latter of which rests upon the supporting structure 8. To the seat flange 6 is secured, at spaced intervals, a plurality of bridge members 9 each of which is provided with a boss 11 positioned centrally of the bridge. Threaded in to each of the bosses 11 is a screw 12, each of which is provided with a large flat bottomed head 13, formed with a central recess 14 on the lower end thereof, so as to form a good clamping edge. The bridge members 9 and the screws 12 form the clamping means for securing the sash parts together.

Resting on the foot flange 7 of the stationary member is the adjustable member 15, having at its upper edge the inwardly turned glass-engaging flange 16 and at the lower edge the inwardly turned foot flange 17. The end of the foot flange 17 is formed with a plurality of raised beads 18 extending at intervals lengthwise of the flange.

Means are provided for fixedly connecting the adjustable member to the fixed member and comprise a plurality of angle shaped tie bars. Each of the tie bars comprises a lower arm 19 and a side arm 21. The top end of the side arm 21 is adapted to engage behind the glass-engaging flange 16 of the adjustable member, and the lower arm 19 is formed with a raised bead 22 adapted to seat over, and be interlocked with, one of the raised beads

- 18 of the adjustable member. To the lower arm 19 of each tie bar is secured a strip of deformable material 23, preferably lead, corrugated to enhance its deformability, and adapted to overlie the seat flange 6 of the fixed member. The side edges 20 of the lower arm 19 are bent over so as to engage the side edges of the deformable strip, and that portion of the lower arm between the bent over edges is preferably corrugated to form a seat for the deformable strip with which it interlocks, thus co-acting with the bent over edges to firmly hold the deformable strip in place. When the head 13 of the screw 12 is imbedded tightly in the deformable material, the tie bar is firmly locked in place without placing any tension on it that would tend to put undesired stresses on the glass.
- 20 So as to prevent the top flange 4 of the fixed member of the sash from becoming distorted by workmen stepping thereon, and by objects falling thereon before the sash has been completely assembled, I provide the screws 12 of such length as to engage the underside of the top flange 4 when sufficiently backed out from the bridges 9. The screws in this way form an efficient support for the top flange. The upper end of the screws 12 are slotted at 24 to provide means for turning the screws, and the top flange 4 is provided with apertures 26 positioned directly above the screws 12 to permit access thereto.
- 25 So as to permit the stationary member of the sash to be readily and easily set in place when installing the sash, I provide a plurality of rivets 27, having large heads 28 which underlie the seat flange and rest upon the supporting structure 8 to serve as a leg and support for the seat flange. The rivets 27 may be arranged to co-act with rivets 29 in securing the bridges 9 to the seat flange 6, or they may entirely supplant the rivets 29.
- 30 Of course the screw is inserted before the bridge is riveted. This bridge and screw assembly is particularly valuable because screws cannot be lost after they are once placed in the bridge.
- 35 I claim:
- 50 1. A sash for holding plate glass comprising a stationary bar adapted to engage one side of the glass, an adjustable bar adapted to engage the other side of the glass, a tie bar fixed to said adjustable bar and engageable with said stationary bar, a bridge secured to said stationary bar, and a screw threaded in said bridge for clamping said tie bar to said stationary bar when said bars are in assembled position.
- 55 2. A sash for holding plate glass comprising a stationary bar adapted to engage one side of the glass, an adjustable bar adapted to engage the other side of the glass, a tie bar fixed to said adjustable bar and engageable with said stationary bar, a bridge secured to
- 60 3. A sash for holding plate glass comprising a stationary bar adapted to engage one side of the glass, an adjustable bar adapted to engage the other side of the glass, a tie bar fixed to said adjustable bar and engageable with said stationary bar, a bridge secured to said stationary bar when said bars are in assembled position and for supporting a portion of said stationary bar on said bridge prior to the assembling of the sash.
- 65 4. A sash for holding plate glass comprising a stationary bar adapted to engage one side of the glass and having a base flange provided with a seat, an adjustable bar adapted to engage the other side of the glass, a tie bar fixed to said adjustable bar and engageable with said stationary bar, a bridge secured to said base flange and positioned over said seat, and a screw threaded in said bridge for securing said tie bar to said stationary bar when said bars are in assembled position.
- 70 5. A sash for holding plate glass comprising a stationary bar adapted to engage one side of the glass and having a base flange provided with a seat, an adjustable bar adapted to engage the other side of the glass, a tie bar fixed to said adjustable bar and engageable with said stationary bar, a bridge secured to said base flange and positioned over said seat, a screw threaded in said bridge and having a head on the lower end thereof adapted to coact with said seat in clamping said tie bar thereto.
- 75 6. A sash for holding plate glass comprising a stationary bar adapted to engage one side of the glass, an adjustable bar adapted to engage the other side of the glass, a tie bar fixed to said adjustable bar and having a deformable end adapted to overlie the stationary bar, and a screw carried by said stationary bar and having a substantially flat bottomed head provided with a recessed portion and engageable with the deformable end of said tie bar for clamping the tie bar to said stationary bar.
- 80 7. A sash for holding plate glass comprising a stationary bar adapted to engage one side of the glass, an adjustable bar adapted to engage the other side of the glass, a tie bar fixed to said adjustable bar and having a deformable end adapted to overlie the stationary bar, and a screw carried by said stationary bar and having a substantially flat bottomed head provided with a centrally disposed flat bottomed recess and engageable with the deformable end of said tie bar for clamping the tie bar to said stationary bar.
- 85 8. A sash for holding plate glass comprising a stationary bar adapted to engage one side of the glass and having a seat flange, an adjust-

- able bar adapted to engage the other side of the glass, a tie bar secured to the adjustable bar and extending over said seat flange, means for clamping the tie bar to the seat, and a supporting leg underlying said seat flange. 5
9. A sash for holding glass comprising a stationary bar adapted to engage one side of the glass and having a seat flange, an adjustable bar adapted to engage the other side of the glass, a tie bar secured to the adjustable bar and extending over said seat flange, a bridge arranged on said seat flange, and a rivet fastening the bridge to the seat flange and having a large head forming a supporting leg underlying said seat flange. 10
10. In a sash for holding glass a tie bar formed with an arm having inwardly folded edges, and a strip of deformable material se- 15
- cured to said arm within said inwardly folded edges. 20
11. In a sash for holding glass a tie bar formed with an arm having a corrugated area, and a piece of soft metal overlying the corrugated area. 25
12. In a sash for holding glass a tie bar formed with an arm having a corrugated area, a piece of soft metal embedded in said corrugations and means for retaining the strip in place. 30
13. In a sash for holding glass a tie bar formed with an arm having a corrugated area, and a piece of soft metal overlying the corrugated area and interlocked with said arm.

In testimony whereof, I have hereunto set my hand.

DANIEL J. MURNANE.
